Primary Examiner — Darlington Ly(74) *Attorney, Agent, or Firm* — Kowert, Hood, Munyon, Rankin & Goetzl, P.C.; Gareth M. Sampson(57) **CLAIM**

The ornamental design for an electric motorbike, as shown and described.

DESCRIPTION

FIG. 1 is a front and right side perspective view of an embodiment of an electric motorbike;
FIG. 2 is a front elevational view thereof;
FIG. 3 is a rear elevational view thereof;
FIG. 4 is left side elevational view thereof;
FIG. 5 is right side elevational view thereof; and,
FIG. 6 is a top plan view thereof.
The broken lines are included for the purpose of illustrating portions of the article and form no part of the claimed design.

1 Claim, 6 Drawing Sheets(56)
